(57) **CLAIM**

The ornamental design for a twisting barrel pet chew, as
shown.

DESCRIPTION

FIG. 1 is a perspective view of a first embodiment of a twisting
barrel pet chew of the present invention;

FIG. 2 is a top view of the twisting barrel pet chew of FIG. 1;
FIG. 3 is a bottom view of the twisting barrel pet chew of FIG.
1;

FIG. 4 is a left side view of the twisting barrel pet chew of
FIG. 1;

FIG. 5 is a right side view of the twisting barrel pet chew of
FIG. 1;

FIG. 6 is a front view of the twisting barrel pet chew of FIG.
1; and,

FIG. 7 is a back view of the twisting barrel pet chew of FIG.
1.
